Inventor

Olof Ohlsson,

By Draket Co Atty's.

UNITED STATES PATENT OFFICE.

OLOF OHLSSON, OF NEWARK, NEW JERSEY.

CENTRIFUGAL BUTTER-EXTRACTOR.

SPECIFICATION forming part of Letters Patent No. 621,127, dated March 14, 1899.

Application filed July 5, 1893. Renewed January 10, 1899. Serial No. 701,766. (No model.)

To all whom it may concern:

Be it known that I, OLOF OHLSSON, a subject of the King of Sweden and Norway, residing at Newark, in the county of Essex and State of New Jersey, have invented certain new and useful Improvements in Centrifugal Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in centrifugal machines; and it has for its object to provide a centrifugal machine that may be readily converted from a cream-separator to a butter-extractor, and vice versa, to provide a detachable cream-disturber for a centrifugal machine that is simple and economical in its construction and effective in its operation, to provide a cream-disturber that may be easily and accurately regulated to vary its work in accordance with the amount of work required to make butter, and to provide a cream-disturber that will automatically regulate itself so as to vary its work in accordance with the amount of work required to make butter.

The invention consists of the construction hereinafter set forth.

In the drawings forming part of this specification, and in which like letters of reference designate similar parts throughout, Figure 1 is a central vertical section of the cover of a centrifugal machine embodying one form of the invention. Fig. 2 is a plan view, and Fig. 3 is an end view, of a cream-disturber embodying part of the complete invention. Fig. 4 is a vertical section, and Fig. 5 is a plan view, of a plug or diaphragm employed when the machine is worked as a separator.

Referring now more particularly to the embodiment of the invention shown in the drawings, *a* is a cover for the bowl of a centrifugal machine.

b is an inlet-duct for the full milk, leading into a reception-chamber *c*, from which the duct *c'* carries the milk to the bowl.

h is an ordinary duct to permit the escape

of cream or butter according as the machine is worked as a separator or extractor.

The reception-chamber is closed at the bottom by a removable plug or piece generally screw-threaded. If the machine is not to be used as a butter-extractor, a plain filling-piece *f'* will be used to close this chamber; but if the machine is to be employed as a butter-extractor the bearing block or piece *f* will be used. This piece *f* has a bearing in which works a pivot *e*, provided with milk-lubricating duct *i* and carrying a suitable cream-disturber *g*, adapted to work in the liquid-space of the bowl and especially that part occupied by the cream-wall *A*. The pivot fits its bearing closely, but is free to move independently of the bowl or at a different rate of speed; but being in frictional engagement with the bowl it would tend to move therewith and at the same rate of speed. The disturber may vary widely in form; but in the preferred form it consists simply of two arms *g''*, fixed to a hub *g'* and carrying blades *g'''*. The hub is secured to the pivot *e* in any convenient manner, as by screwing it onto the threaded extension *e'* of the pivot *e*. Connected with the pivot *e*, and hence with the disturber *g*, is some suitable means adapted to retard or impede the movement of the disturber *g*, so that the disturber when carried around with the rotating milk within the bowl may be impeded and caused to move at a slower rate of speed than this rotating milk. It is of course obvious that when the bowl is empty and is set in motion the pivot *e* and disturber *g* will move with the bowl and at substantially the same rate of speed unless its movement is in some way impeded and that if the bowl is supplied with milk, so that the disturber dips into the milk, the disturber will rotate at substantially the same speed as the surrounding liquid, whether this speed be equal to or less than that of the bowl, in case there is nothing to retard the disturber. In this case the disturber would have no material effect upon the milk or cream. If, however, the disturber is retarded, so as not to move as fast as the liquid rotates, then the disturber will act upon the cream and by a gentle disturbance and agitation of its particles turn it into butter.

Any suitable retarding means may be

employed that is adapted to accomplish the purpose of impeding the disturber, so that it will move at a slower rate of speed than the milk in the bowl, so as to turn the cream into butter. In the drawings, which show the best form of the invention now known to me, the retarding device is in the form of a bowl or receptacle *d*, fixed to the pivot *e* and located in the reception-chamber *c*, beneath the inlet-duct *b*, whereby it receives the inflowing milk before it passes into the bowl, so that the speed of the disturber will be automatically regulated.

The inflowing milk as it enters the retarding-receptacle *d* serves as an impediment to the rotation of the receptacle and disturber, and in order that the inflowing milk may check the receptacle *d* and disturber more positively the receptacle may be provided with fixed wings *d'*. The great advantage of this arrangement is that the effective operation of the disturber is automatically regulated so as to correspond with the work required in making butter. It is well known that there has heretofore been great difficulty found in securing just the proper amount of agitation of the cream in a butter-extractor to produce the best results. The great difficulty has been to prevent excessive agitation of the cream and the consequent bad flavor and poor quality of the butter. The constant care of an attendant has generally been required to prevent this undue agitation, and even then it was very difficult and often impossible to prevent the butter from being spoiled by excessive agitation of the cream. In accordance with this invention it is possible to secure the exact amount of agitation required to make butter without spoiling it and to automatically regulate the amount of agitation so as to correspond with the work required. The disturber, it will be seen, is set in motion by the rotating bowl of the machine, which gives also a rotary movement to the contained liquid, and this movement of the disturber, which may be occasioned by frictional contact with some moving part of the bowl, as shown in Fig. 1, or by some other suitable form of engagement, is retarded by the non-rotary inflowing milk. It is of course obvious that the disturber need not necessarily depend for its movement upon any mechanical engagement, frictional or otherwise, with the bowl, because if the disturber were free from such mechanical engagement it could be actuated by the milk rotating within the rotating bowl into which the disturber dips. In this latter case the rotating milk would itself carry the disturber around. Moreover, the movement of the disturber could be occasioned partly by the bowl with which it might be in engagement and partly by the rotating milk. The faster a given quantity of the liquid flows into and out of the bowl the shorter will be the period of its agitation, due to the disturber, and the greater, therefore, must be the degree of agi-

tation. Conversely, the slower this given quantity of the liquid flows into and out of the bowl the longer will be its period of agitation, due to the disturber, and the less, therefore, must be the degree of agitation. By employing the inflowing milk or a certain percentage of it to retard the disturber the degree of agitation will correspond with the amount of liquid passing into and out of the bowl. If more liquid flows into and out of the bowl, then the disturber will be more retarded, and if less liquid flows into and out of the bowl then the disturber will be less retarded. Thus it will be seen that by employing the inflowing milk to retard the disturber the precise amount of agitation required to make butter of excellent flavor and quality may be secured. The disturber is preferably located near the butter-outlet duct *h*, as shown in Fig. 1, and its slanting blades serve to prevent the cream from lingering at the cream-wall and to assist the butter to flow evenly from the machine.

It will be seen that the centrifugal machine may be readily converted from a cream-separator to a butter-extractor, and vice versa, by simply interchanging the bearing block or piece, as *f*, with the disturber and a plain filling block or piece, as *f'*.

While the advantages of my entire invention are best secured by arranging the disturber to be automatically regulated in the manner above set forth, yet some of the advantages may be secured by regulating the disturber by hand or otherwise. Moreover, the particular embodiment of the invention may be considerably varied in form and arrangement from that shown in the drawings, as will be readily understood, without departing from the spirit and scope of the invention.

What I claim as new, and desire to secure by Letters Patent, is—

1. In a centrifugal machine, a disturber located in the liquid-space of the bowl and adapted to move in the same direction as the bowl and means connected or associated with the disturber adapted in the normal operation of the machine to reduce or retard the speed of the disturber below that of the rotating liquid within the bowl, substantially as set forth.

2. In a centrifugal machine, a disturber located in the liquid-space of the bowl and in rotative engagement with the bowl and adapted to move in the same direction as the bowl, and means connected or associated with the disturber adapted in the normal operation of the machine to reduce or retard the speed of the disturber below that of the rotating liquid within the bowl, substantially as set forth.

3. In a centrifugal machine, a liquid-disturber located in the liquid-space of the bowl and adapted to move in the same direction as the bowl, the disturber being provided with means whereby it is adapted in the normal operation of the machine to be controlled as

- to its speed by the liquid flowing to the bowl, so that the effective energy of the disturber is automatically adjusted to correspond with the flow of liquid, substantially as set forth.
5. In a centrifugal machine, a cream-disturber pivotally secured in the axis of rotation of the bowl and located in the liquid-space of the bowl and said disturber being provided with a retarding device controlled by liquid flowing to the bowl whereby the speed of the disturber is controlled by liquid flowing to the bowl, substantially as set forth.
10. In a centrifugal machine, a cream-disturber pivotally secured in the axis of rotation of the bowl and located in the liquid-space of the bowl and said disturber being provided with a retarding device adapted in the normal operation of the machine to reduce the speed of the disturber below that of the rotating liquid within the bowl, substantially as set forth.
15. In a centrifugal machine, a cream-disturber pivotally secured in the axis of rotation of the bowl and located in the liquid-space of the bowl and said disturber being provided with a retarding device controlled by liquid flowing to the bowl whereby the speed of the disturber is controlled by liquid flowing to the bowl, substantially as set forth.
20. In a centrifugal machine, a cream-disturber pivotally secured in the axis of rotation of the bowl and located in the liquid-space of the bowl and said disturber being provided with a retarding device adapted in the normal operation of the machine to reduce the speed of the disturber below that of the rotating liquid within the bowl, substantially as set forth.
25. In a centrifugal machine, the combination of a bowl provided with a removable bearing block or piece, a cream-disturber pivoted in said bearing-block in the axis of the bowl's rotation and disposed in the liquid-space of the bowl and means connected or associated with the disturber and adapted in the normal operation of the machine to retard the speed of the disturber below the speed of the rotating liquid within the bowl, substantially as set forth.
30. In a centrifugal machine, the combination of a bowl provided with a removable bearing-block in its top, a cream-disturber pivoted in said block in the axis of the bowl's rotation, and disposed in the liquid-space of the bowl and actuated by the bowl, and a receptacle in engagement with the disturber adapted to receive the inflowing milk and reduce the speed of the disturber below the speed of the rotating milk within the bowl, substantially as set forth.
35. In a centrifugal machine, a bowl provided with a reception-chamber for the inflowing milk, a cream-disturber disposed within the liquid-space of the bowl and fixed to a pivot passing through the reception-chamber into the bowl, whereby the disturber is actuated by the bowl, a retarding device located in the reception-chamber and fixed to the pivot and adapted to be operated upon by the inflowing milk, substantially as set forth.
40. In a centrifugal machine, the bowl having a reception-chamber *c* in its top, a pivot *e* passing through the bottom of the reception-chamber, a cream-disturber *g* fixed to the pivot within the bowl and having inclined blades *g'''*, a retarding-receptacle *d* seated on the pivot *e* in the reception-chamber *c*, the arrangement being such that the disturber is actuated by the bowl but is reduced in speed below that of the rotating liquid within the bowl by the inflowing milk in the retarding-receptacle, the amount of retardation being dependent upon the rate of inflow of milk into the machine, substantially as set forth.
45. In a centrifugal machine, a liquid-disturber located in the liquid-space of the bowl and adapted to move in the same direction as the bowl, and means connected or associated with the disturber adapted in the normal operation of the machine to automatically reduce or retard the speed of the disturber below that of the rotating liquid within the bowl, substantially as set forth.
50. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
55. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
60. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
65. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
70. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
75. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
80. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
85. In a centrifugal machine, a liquid-disturber located in the liquid-space of the bowl and in rotative engagement with the bowl so as to move in the same direction therewith, and means connected or associated with the disturber adapted in the normal operation of the machine to automatically reduce or retard the speed of the disturber below that of the rotating liquid within the bowl, substantially as set forth.
- In testimony that I claim the foregoing I have hereunto set my hand this 21st day of June, 1893.
